UNITED STATES PATENT OFFICE.

JOHN M. COOK, OF CINCINNATI, OHIO.

GRATE FIRE-PLACE.

SPECIFICATION forming part of Letters Patent No. 247,485, dated September 27, 1881.

Application filed December 31, 1880. (No model.)

To all whom it may concern:

Be it known that I, JOHN MALCOLM COOK, of Cincinnati, Ohio, have invented certain new and useful Improvements in Grate Fire-Places, 5 of which the following is a specification.

The object of my invention is to economize fuel and radiate into the room the heat usually absorbed by the walls of the fire-place or carried up the flue by means of a device which 10 can be cheaply made, will occupy but little space in the room, and will present the neat and cheerful appearance of the ordinary grate fire-place. These objects are accomplished by the means illustrated in the accompanying 15 drawings, in which—

Figure 1 is a front elevation of my improved grate fire-place. Fig. 2 is a transverse horizontal sectional plan taken above the grate or fire-basket in line $x-x$ of Fig. 1, and Fig. 3 is 20 a central vertical transverse section.

Referring to the parts, which are indicated by identical letters throughout the various views, A is a sheet-metal plate of a size to cover the customary grate-opening in the chimney 25 and rest against the wall surrounding the opening.

The fire-back B is a segment of a corrugated dome-shaped shell, made preferably of cast-iron. It has a thimble, b, which projects from 30 its back through plate A, to receive a pipe which extends into the flue, and the customary lugs are cast upon it to support the grate C. The fire-back is held in place by a perforated molded frame, D, the inner front portion of 35 which rests against the front edge of the fire-back B. The purpose of the perforations in frame D is to provide for the admission of air through the lower ones, and permit of its escape into the room through the upper ones after 40 it has been heated. The front D and plate A

are secured together at their outer edges, firmly holding the fire-box between them.

The grate C is supported upon the lugs cast upon the inside of the fire-back by journal-pins extending from the end bars. One of these 45 journals extends through the back B and front D, and has a square or angular end to receive a key or wrench, by which the grate may be shaken or tilted to free it of ashes.

Within the pipe or curved thimble b is a 50 damper, E, which is actuated by a rod, e, which extends through the front D, and has a knob or handle upon its outer end, by which the damper may be turned to regulate the draft.

My improved grate fire-place is secured in 55 front of the ordinary fire-place opening by the back plate, A, being held firmly against the wall. The back may have around its outer edges inwardly-projecting flanges to retain a lining of asbestos or other non-conducting material, so as to insure a more perfect radiation 6c of the heat given off by the fire-back into the room.

I claim—

A fire-place grate adapted to be set on the 65 hearth in front of and covering the opening of an ordinary fire-place, constructed substantially as before set forth—that is to say, of a back plate, a grated fire-box adjacent thereto, and provided with a smoke-flue projecting 70 through an opening in said back plate, and a fire-box inclosing and retaining frame, which forms an ornamental front, and is perforated to allow the heat radiated from the rear of the fire-box to enter the room.

JOHN MALCOLM COOK.
